BUILDER MECHANISM

Filed April 17, 1924

Attorneys

Patented Apr. 21, 1925.

UNITED STATES PATENT OFFICE.

ROBERT W. GOSSETT, OF SPARTANBURG, SOUTH CAROLINA, ASSIGNOR TO MANUFACTURERS' EQUIPMENT COMPANY, OF SPARTANBURG, SOUTH CAROLINA, A CORPORATION OF SOUTH CAROLINA AND NORTH CAROLINA.

BUILDER MECHANISM.

Application filed April 17, 1924. Serial No. 707,129.

To all whom it may concern:

Be it known that I, ROBERT W. GOSSETT, a citizen of the United States of America, and a resident of Spartanburg, county of 5 Spartanburg, and State of South Carolina, have invented certain new and useful Improvements in Builder Mechanisms, of which the following is a full and clear specification.

10 This invention relates to that well-known type of builder mechanism employed in spinning-frames in which the ring-rail is given a transverse movement, with a gain at the end of the up movement and an equivalent loss at the end of the down movement, means being provided whereby the ring-rail is given a specially-controlled traverse at the beginning of the winding to thereby preliminarily wind on the spindle 15 a bunch. The special object of the present invention is to provide a simple bunch-forming mechanism that may be used in connection with any of the well-known builder mechanisms now in general use.

20 In the drawing—

Fig. 1 is a side elevation of so much of a builder mechanism for spinning-frames as is necessary to show my invention;

Fig. 2 is a vertical sectional view on the line 2—2 of Fig. 1;

Fig. 3 is a vertical sectional view on the line 3—3 of Fig. 2;

Fig. 4 is a horizontal section on the line 4—4 of Fig. 3;

35 Figs. 5 and 6 are detail views of my improved half-pulley.

In the drawing annexed, 10 designates the usual pivoted builder-bar which is adapted to be depressed at intervals by the usual 40 cam (not shown) and which carries the usual pick or gain-wheel 11 affixed to a shaft 12 carrying the usual worm 13, this worm having constant mesh with a worm-gear 14 affixed to a chain-pulley 15. The 45 chain or chains 16 from this pulley 15 extend upwardly over a pulley 17 and thence to the quadrant of the usual weighted lifting-lever 18. The foregoing mechanism operates in a manner well known.

50 On the shaft 19, on which is journaled the combined gear and pulley 14—15, is journaled another pulley 20 larger in diameter than the adjacent pulley 15. This pulley 20 is adapted to be clutched to the pulley

15 by means of a clutch consisting of a pin 55 21 mounted in an axial recess in the pulley 15 and normally projected by a coil-spring 22. In the pulley 20 is mounted a thrust-pin 23, this thrust-pin being normally projected by a spring 24 in a direction away from the 60 clutch-pin 21 and being so positioned in the pulley 20 that it will aline with said clutch-pin 21 when the pulleys 15 and 20 are relatively rotated.

To push in the pin 23 and thereby un-clutch the wheel 20 from the pulley 15, I provide a lever 25 pivoted at 25' and having an upstanding arm 27 having a rounded inner face adapted to be forced against the projecting end of pin 23; the lower end of 70 the lever 25 is turned to a horizontal position and extends to a point near the worm-shaft 12 and in the path of a cam 26 affixed to said worm-shaft. This cam 26 is carried by a collar 27 affixed to the shaft by a 75 set-screw 28, thereby permitting the cam to be rotatively adjusted on the worm-shaft. It will be observed that the rotation of the cam 26 will swing the lever 25 on its pivot 25' and thus cause the upstanding arm 27 80 to push the push-pin 23 inwardly far enough to release the wheel 20 from the clutch-pin 21. It is desirable to provide the lever 25 with a weight 29 to keep its horizontal end in contact, or approximately in 85 contact, with the cam 26, and, in order to permit the cam 26 to pass the lever 25, the nose portion 30 of the lever is hinged to the lever at 31 and held in its normal position by a spring 32.

A chain 33 extends from the large pulley 20 to a pulley 33', on the same shaft with the aforesaid pulley 17; and another chain 34 extends from a half-pulley 35 of the usual form to the quadrant of the lifting-lever 18. At the beginning of the operation of the machine, the clutch-pin 21 is in locking engagement with the bunch-chain wheel 20 and the push pin is opposite the upper end of the cam-arm 27. The work of building the bunch is done entirely by the chains 33—34 and the parts cooperating therewith, the main or service-building chain being slightly slack. As is well understood, the first few reciprocations of the builder-bar 105 95 100 give to the ring-rail the traversing action necessary to build the bunch, and thereafter the traversing of the ring-rail is regular to

thereby regularly build up the windings on the bobbin in the usual manner.

To vary the traverse during the making of the bunch, I make the half-pulley 35 rotatively adjustable with respect to the pulley 33. These two pulleys are rigidly attached together by means of clamp-screws 36 tapped into the body of pulley 33' and extending through arcuate slots 37 formed in the body of the half-pulley. The body of the half-pulley is set in an annular recess in the adjacent face of the pulley 33', as shown in Figs. 5 and 6. With this construction, it will be observed that the half-pulley may be rotatively adjusted in either direction to thus vary the length of the traverse of the ring-rail, to thereby provide for building bunches of different lengths.

The length of yarn used in making the bunch is determined by the position of the cam 26. When this cam 26 forces the lower end of lever 25 outwardly, the cam-end 27 of this lever unclutches the pulleys 20 and 15, to thereby slacken the bunch-building chain 33 and thus stop the bunch building. The rotation of the worm-gear and the pulleys 15 and 20 is so slight during the bunch-building operation that the push-pin 23 does not pass from under the cam-finger 27. By 20 rotating the adjusting cam 26 on the worm-shaft, the unclutching action may be brought about sooner or later to thus vary the length of the yarn that is put into the bunch. The length of the bunch on the spindle is varied by rotatively adjusting the half-pulley, as hereinbefore described.

When the bunch-building pulley 20 is released, the work of building then falls entirely on the chain 16. The action then continues as usual until the bobbins are entirely built up, the bunch-chains 33-34 being idle during this work of laying the service layers on the bobbin, altho, of course, the chains 33-34 continue to pay off their pulleys. By the time the bobbin is completed, the freely-running pulley 20 has been carried around by its chain far enough to bring a radial shoulder 38 on a cam 39 carried by the pulley 20 to a point behind a stop 40 pivotally mounted on an adjacent part of the frame and adapted to normally rest on the circumferential edge of cam 39, said stop dropping down behind the shoulder 38 to thereby prevent the pulley 20 rotating in the opposite direction. Then when the operative in the usual manner, through the worm 13, rewinds the main builder chain 16 upon its pulley 15, the pulley 20 will rotate backwardly with it, by reason mainly of the friction generated by the clutch-pin 21 bearing on the adjacent face of the pulley 20, until the shoulder 38 strikes the stop 40. At this point, two things happen practically simultaneously: the clutch-pin 21 has been brought around to a point coincident with

the thrust-pin, thus permitting the clutch-pin to go into locking action with wheel 30; and, secondly, a cam 41 carried by main chain-wheel 15 comes under the stop 40 and lifts the same high enough to permit the shoulder 38 to pass under the stop. The two pulleys are then locked together during the remainder of the rewinding operation, when the mechanism is ready for another building operation.

What I claim as new is:

1. In a builder mechanism for spinning-frames, a chain-pulley carrying a half-pulley, said half-pulley being rotatively mounted on said pulley, and means for locking the half-pulley in each of its adjusted positions against rotation in either direction.

2. In a builder mechanism for spinning-frames, a vibrating builder-bar carrying a worm and a worm-gear and a main chain-pulley rotating with said worm-gear, a chain connecting said pulley to the lifter mechanism, a bunch-building mechanism embodying a bunch-chain and bunch-pulley, a clutch for causing this bunch-pulley to rotate with the aforesaid chain-pulley, and means associated with the worm-shaft for unclutching said two pulleys when the bunch-building is completed.

3. A builder mechanism for spinning-frames embodying a vibratory builder-arm carrying a worm-shaft rotated intermittently by a pick mechanism, a worm-gear connected to a main chain-pulley, chain means connecting this pulley to the lifter mechanism of the machine, and a bunch-building mechanism embodying a rotatively-adjustable cam on the worm-shaft, a bunch-building pulley, a clutch mechanism actuated from said cam, and chain means connecting said bunch-pulley to the aforesaid lifter mechanism.

4. A bunch building apparatus for spinning-frames embodying adjustable means for varying the length of yarn wound in the bunch, embodying an adjustable cam and a clutch actuated thereby.

5. In a bunch building apparatus, adjustable means for varying the length of the bunch on the spindle, embodying a half pulley, a whole pulley, and means for positively locking the half pulley in various rotative positions.

6. In a bunch building apparatus, adjustable means for varying the length of the bunch on the spindle embodying a rotatively-adjustable cam and clutch devices actuated thereby, and also adjustable means for varying the length of yarn forming the bunch.

7. In a builder mechanism for spinning frames, a chain pulley carrying a half pulley, said half pulley being rotatively mounted on said pulley, and means for locking the half pulley in each of its adjusted positions

against rotation in either direction, one of the pulleys being fitted into an annular recess formed in the other pulley.

8. In a builder mechanism for spinning-
5 frames, a vibrating builder-bar carrying a
worm and a worm-gear and a main chain-
pulley rotating with said worm-gear, a chain
connecting said pulley to the lifter mecha-
nism, a bunch-building mechanism embody-
10 ing a bunch-chain and bunch-pulley, a
clutch for causing this bunch-pulley to ro-
tate with the aforesaid chain-pulley, means
associated with the worm-shaft for unclutching
15 said two pulleys when the bunch-build-
ing is completed, and means brought into
operation on the rewind for insuring re-en-
gagement of the clutch members to thus lock
the pulleys together for another operation.

9. In a builder mechanism for spinning-

frames, a vibrating builder-bar carrying a 20
worm and a worm-gear and a main chain-
pulley rotating with said worm-gear, a chain
connecting said pulley to the lifter mecha-
nism, a bunch-building mechanism embody-
25 ing a bunch-chain and bunch-pulley, a clutch
for causing this bunch-pulley to rotate with
the aforesaid chain-pulley, means associated
with the worm-shaft for unclutching said
two pulleys when the bunch-building is com-
30 pleted, and means brought into operation on
the rewind for insuring re-engagement of
the clutch members to thus lock the pulleys
together for another operation, this latter
means embodying a stop on the frame and a
35 cam on each of the pulleys.

In testimony whereof I hereunto affix my
signature.

ROBERT W. GOSSETT.
